R. W. ERICKSON

LOUD SPEAKER

Filed Dec. 2, 1922

INVENTOR
ROBERT W. ERICKSON
BY
D. Anthony Mina
ATTORNEY

UNITED STATES PATENT OFFICE.

ROBERT W. ERICKSON, OF JERSEY CITY, NEW JERSEY.

LOUD SPEAKER.

Application filed December 2, 1922. Serial No. 604,490.

To all whom it may concern:

Be it known that I, ROBERT W. ERICKSON, a citizen of the United States and resident of Jersey City, New Jersey, have invented certain new and useful Improvements in Loud Speakers, of which the following is a specification.

This invention relates to sound reproducing devices and aims to provide improved means for converting electrical impulses into audible sound waves. The device is particularly adapted for use in connection with radio circuits but can be used equally as well on ordinary telephone circuits if desired. The arrangement is such that I can utilize the sound reproducing mechanism of ordinary types of talking machines or phonographs now in general use and thus secure the advantages of a loud speaker without the necessity of installing extra equipment.

In the accompanying drawings which illustrate embodiments of my invention—

Fig. 1 is a perspective view showing the device mounted in position for co-action with the type of talking machine which uses disc records having grooves adapted to vibrate a needle laterally;

Fig. 2 is a sectional view on the line 2—2 of Fig. 1 on a slightly enlarged scale.

Referring first to Figs. 1 and 2 my device includes a base 10 to which is secured a permanent magnet 12 which is held in place by suitable brackets 14. The upper arm of the magnet 12 carries a plate 16 having inwardly extending pole pieces 18 and 20 which support coils 22 and 24. The pole pieces 18 and 20 are separated by a small air gap 26 and extending through this gap is an armature or reed 28 which is preferably made of resilient material and secured by a screw 30 within a slot 32 formed in the lower arm of the magnet 12. At its upper end the armature 28 has secured thereto a plate 34. This plate 34 provides a convenient surface with which the usual needle 36 of a phonograph reproducer may be swung into engagement.

In Fig. 1 I have illustrated a reproducer 38 having a diaphragm 40 carried thereby, said reproducer being mounted on the usual crooked arm 42 which is pivoted at 43 to the usual tone-arm 44 and this tone-arm is in turn connected with the usual horn diagrammatically illustrated at 46.

In operation the current from the radio apparatus passes through the wires 48 and 50 through suitable connections in the base

19, not shown, and to the coils 22 and 24. This current vibrates the armature or reed 28 at varying frequencies, as well understood in this art, in such a manner that the vibrations can be converted into sound. By swinging down the reproducer 38 about the pivotal connection 43 on the end of the tone-arm I bring the needle 36 of the reproducer into frictional engagement with the plate 34 carried by the armature 28. In this way I am enabled to effectively transmit the vibrations of the armature 28 to the diaphragm 40 of the reproducer by mere frictional contact between the needle 36 and the plate 34 on the end of the armature. The sound produced by the diaphragm is amplified by the horn 46.

From the above it will be perceived that my invention provides means whereby ordinary types of talking machines or phonographs may be utilized as adjuncts to radio receiving apparatus and that no particular complex connections need be made with such talking machines, it being merely necessary to mount my device in such position that the needle or record-engaging element of the talking machine reproducer will frictionally engage the armature of my device, it being appreciated that the small vibratory movements of the armature can readily be transmitted by direct contact with the reproducer in this way.

The coils 22 and 24 which connect with the wires of the radio apparatus receive therefrom a current of varying intensity in the opposite coils and exert a varying pull on the reed or armature. These are the only coils that are necessary, so that the whole apparatus is very simple and cheap. The armature or reed is merely in effect a part of pole of the permanent magnet.

By the provision of a comparatively broad flat plate on the end of the armature, it is possible to bring the apparatus very quickly into sufficiently close register with the needle of the phonograph. That is, the needle may drop onto any part of the flat end of the armature and will make frictional contact at all points. Also this arrangement avoids the cramping or binding action which would take place if the needle had to fit into a socket unless the armature were brought into very exact register, a thing which is difficult or at least requires care and time.

Though I have described with great particularity the details of the specific embodiments of the invention shown, it is not to be

construed that I am limited thereto as changes in arrangement and substitution of equivalents may be made by those skilled in the art without departing from the invention as defined in the appended claims.

What I claim is:

1. A device for converting electrical impulses into sound comprising an armature arranged to be vibrated electrically, a sound producing diaphragm and an operating member therefor, said armature having a comparatively broad flat surface adapted at all points to make frictional contact with said member and to transmit to it the vibrations of the armature the arrangement being such that the amplitude of vibrations transmitted remains the same regardless of the point of contact between said member and the broad surface of the armature.
2. A device of the class described comprising a resilient armature and a magnet including a pair of pole pieces surrounded by coils located on opposite sides of said armature in juxtaposition to the free end thereof, and adapted to be connected to the

wires of a radio or similar apparatus so as to receive a current of varying intensity in the opposite magnets, a sound reproducing diaphragm and an operating member therefor removably engaging said armature the latter having an enlarged head for frictional engagement with said member.

3. A device of the class described including a double-pole permanent magnet, a resilient magnetic armature mounted in proximity to one pole of the latter, a magnetic yoke having a winding thereon mounted in proximity to the opposite pole of said permanent magnet, the ends of said magnetic yoke being located at opposite sides of said armature in juxtaposition to the free end thereof, said armature having a flat surface on its free end in a plane perpendicular to its length and arranged to transmit movements of the armature to a sound producing diaphragm by mere frictional contact with said flat surface.

In witness whereof, I have hereunto signed my name.

ROBERT W. ERICKSON.
